UNITED STATES PATENT OFFICE.

MORRIS MARTIN, OF MALDEN, MASSACHUSETTS, ASSIGNOR TO THE MUNICIPAL SIGNAL COMPANY, OF PORTSMOUTH, NEW HAMPSHIRE.

SIGNAL-BOX.

SPECIFICATION forming part of Letters Patent No. 425,576, dated April 15, 1890.

Application filed February 25, 1887. Serial No. 228,830. (No model.)

To all whom it may concern:

Be it known that I, MORRIS MARTIN, of Malden, county of Middlesex, and State of Massachusetts, have invented an Improvement in 5 Signal-Boxes, of which the following description, in connection with the accompanying drawings, is a specification, like letters on the drawings representing like parts.

This invention has for its object to construct a signal-box adapted to transmit two different kinds of signals—such, for instance, as fire-alarm and police-alarm signals—by means accessible at the exterior of the box, and also to transmit other signals by means 15 accessible at the interior of the box.

In accordance with this invention the box contains a multiple transmitter, a pointer or indicating means for determining the signal to be transmitted, and an actuating member, 20 as a pull, for the transmitter. The box is also provided with a door concealing the pointer and the actuating-pull, and also with two key-holes which are accessible from the exterior of the box, as when the box-door is closed. 25 Two independent actuating mechanisms besides the actuating member or pull above referred to are employed for actuating the transmitter, the said actuating mechanisms being respectively operated by keys inserted 30 in the two key-holes. To enable the two independent actuating mechanisms to operate the transmitter to transmit each a different signal a switch is provided which introduces into the line a co-operative part of the multiple 35 transmitter, which part is normally cut out. The actuating mechanisms are so constructed and arranged with relation to adjacent parts of the box as to lock the key which is employed to move them when once inserted in 40 the key-hole and turned, the said key being afterward released, preferably by opening the box-door.

Figure 1 shows in front elevation a signal-box embodying this invention, the door being open; Fig. 2, a rear side view of the face-plate, which is concealed by the door and which has the operating parts secured to it; Fig. 3, a vertical section of one of the actuating mechanisms containing the switch; Fig. 4, a section of the actuating mechanism shown in

Fig. 3, taken on the dotted line xx ; and Fig. 5, a diagram showing a circuit containing a multiple signal-transmitter and suitable receiving apparatus.

The box or case A has a face-plate a and a door A' fitted to it. A suitable frame a' is secured to the rear side of the plate a , as shown in Fig. 2, said frame supporting a multiple signal-transmitting device, preferably of the construction shown and described in 55 United States Patent No. 320,032, to which reference may be had, said multiple signal-transmitting device comprising a motor and a series of break-wheels, as m m' , &c., contact-pens therefor, a starting-lever m^2 , and an actuating-pull c for the starting-lever.

I have herein shown a non-interfering mechanism comprising a pivoted locking device d^x , which is substantially the same as shown and described in an application for Letters Patent 70 of the United States filed by me, Serial No. 222,330, to which reference may be had, the function of the locking mechanism and its co-operation with the neighboring parts being to prevent tampering with the signal, as 75 set forth in the said application.

The actuating-pull c is provided with a finger-piece c' , passing through a slot or opening o in the plate a , so that the transmitter may be set in operation by depressing the pull to 80 transmit any signal desired, depending upon the condition of the transmitter, and, in the present instance, which contact-pen is thrown in contact with its break-wheel by the selecting-cylinder p^x , rotated by a pointer p^x , 85 which is moved over a stationary dial.

At the lower end of the plate a two key-holes $n' n'$ are cut and at the rear side of each key-hole an actuating mechanism is situated, supported in a frame n^2 , which frame consists 90 of two disks $e' e^2$, rigidly connected together by a shank portion and secured to the plate by the side pins 20. The actuating mechanism at the rear side of the key-hole n' consists of a wheel or pulley e , mounted upon the shank portion connecting the two disks $e' e^2$. The wheel or roller e is provided at one side with a pin or stud e^3 , which passes through a curved slot e^4 , cut in the disk e' near its periphery, so that the said disk or roller may be 100

rotated for a distance corresponding with the length of the slot. One end of a chain or cord *b* is secured to the periphery of the roll *e* by a pin or other suitable fastening, the opposite end of the chain being secured to the actuating-pull *c*, so that as the roll is revolved the chain or cord will be drawn to move the pull, and thereby operate the transmitter. A plug *p* passes through the frame *n*², the rear end *p'* of the plug projecting outward from the frame into the key-hole to enter the socketed end of a key.

When the key is inserted, the portion *p'* enters the socketed end of the key far enough to permit the end of said key to bear against a shoulder or flange *f* of the plug, and then by a still further movement of the key the said plug will be pushed forward that its forward end *p* may rub against the contact-springs *p*², which are secured to insulated blocks *p*³, attached to the disk *e*² of the frame *n*². The key having been thus inserted, it may be rotated until its bit strikes the pin or stud *e*³, and by still further rotation may rotate the roll *e*, to thereby pull the cord or chain.

A spring-controlled detent *d* is pivoted to the rear side of the plate *a*, which lies in the path of movement of the bit of the key to be moved by said bit, and to be returned to its normal position by a spring after the bit has passed beyond it to prevent backward rotation of the key, and consequently its withdrawal from the key-hole. The key-hole is enlarged or elongated at its upper side to permit the key to be withdrawn; but such opening is covered by the door of the box, and also receives a projection cast on the inside of the door, so that unless the door be opened the key cannot be removed. This form of locking device is substantially the same as in the application above referred to. The plug *p* is held out of engagement with the contact-springs *p*² by a bifurcated spring *p*⁴.

The actuating mechanism at the rear side of the key-hole *n* is substantially the same as that just described, the switch-plug *p*, however, being omitted, and the chain or cord *b* is extended and attached to the periphery of the roller of this actuating mechanism, as shown in Fig. 2.

It will be seen that by the two actuating mechanisms described the actuating member of the transmitter may be moved by operating either of the said mechanisms by their respective keys.

As it is designed that one of the actuating mechanisms should effect through the transmitter the transmission of a signal different from that effected by the other—as, for instance, one should cause a fire-alarm signal and the other a police-alarm signal to be transmitted—it is the function of the switch-plug *p*, above described, to cut in and out that operative part of the multiple signal-transmitter which is employed to transmit the particular signal desired.

By referring to Fig. 5, a diagram is shown fully illustrating the manner in which the box-number will always be transmitted, either alone or in conjunction with any special signal desired. The break-wheel *m* is arranged to transmit the box-number, and, together with its contact-pen, is continually in the main line *L*, so that whenever the actuating pull or member of the transmitter is operated the break-wheel will revolve. The break-wheel *m'* is arranged to transmit a special signal—as, for instance, a signal indicating "fire"—and said break-wheel, with its contact-pen, is connected by a wire *l'*, with one of the contact-springs *p*², while the other contact-spring *p*² is connected with the main line *L* by a wire *l*, so that when the switch-plug *p* is pressed forward and connection made with the two contact-springs the said break-wheel *m'* will be in circuit. Each break-wheel *m* *m'* has that portion of its surface which does not contain the notches or breaks cut away, and the break-wheels are so arranged with relation to each other that while the pen of one break-wheel is passing over the notched portion thereof the pen of the other break-wheel is disengaged from its break-wheel by the cut-away portion, and vice versa, so that one signal—as, for instance, a fire-alarm signal—may be transmitted, followed by the box-number. The main line *L* contains a battery *L'* and a relay *L*², which effects the operation of a suitable receiving-instrument.

By thus providing a signal-box with two independent actuating mechanisms accessible by keys from the exterior of the box, and also with a switch which is moved by one of the keys, two different signals may be transmitted by means of a single-transmitting apparatus contained in the box.

I claim—

1. In a signal-box, a multiple signal-transmitter having a manual signal-selecting device adapted to be moved to set the transmitter for different signals, and a switch co-operating with the said transmitter for an additional signal, and an actuating device or pull for the transmitter, combined with two additional actuating devices for the transmitter and keys therefor, the said switch being moved by one of said keys, substantially as described.

2. In a signal-box, a multiple signal-transmitter and pull or actuating device for it concealed by a door and another actuating device for it accessible from the exterior of the box, combined with a third actuating device for the said transmitter, accessible from the exterior of the box, a key for it, and a switch moved by the said key for including a co-operative part of the said transmitter, substantially as described.

3. In a signal-box, a multiple signal-transmitter, a pull for it, and an actuating device operatively connected with said pull by a chain or cord, and a key for said actuating device, combined with another actuating de-

vice operatively connected to said pull, a key for it, and a switch moved by the insertion of said key for including a co-operative part of said transmitter, substantially as described.

5 4. In a signal-box, a multiple signal-transmitter and pull or actuating device for it concealed by a door, combined with another actuating device for the said transmitter, accessible from the exterior of the box, a key for it, and a switch moved by the said key for

including a co-operative part of the said transmitter, substantially as described.

In testimony whereof I have signed my name to this specification in the presence of two subscribing witnesses.

MORRIS MARTIN.
